UNITED STATES PATENT OFFICE.

LOUIS RUFFIO, OF NEW YORK, N. Y.

WOMAN'S HEADDRESS.

Application filed April 11, 1925. Serial No. 22,290.

This invention relates to women's head-dress, and more particularly is directed to an improved head-dress having an elastic body portion for supporting strands of hair 5 and further including means for securely fastening the head-dress to the head of the wearer, said head-dress being especially adapted for use by women having bobbed hair to give the same the appearance of long 10 hair when desired.

An object of the invention is to provide an improved head-dress of the character described which may be simply and quickly attached to the head of the wearer and which 15 is adjustable for various sizes and shaped head contours, thus assuring a comfortable and snug fit when applied in position.

A further object of the invention is to provide a head-dress of the character and 20 for the purpose described which is simple and relatively inexpensive to manufacture, neat in appearance, and practical for providing various desired styles of coiffure.

Other objects of this invention will in 25 part be obvious and in part hereinafter pointed out.

Certain features herein shown and described, are shown, described and claimed in my co-pending application Serial No. 3,248, 30 filed January 19th, 1925, and accordingly are not claimed herein.

With the above exception, the invention accordingly consists in the features of construction, combinations of elements and arrangement of parts which will be exemplified in the construction hereinafter described 35 and of which the scope of application will be indicated in the following claims.

In the accompanying drawing, in which 40 is shown one of the various possible illustrative embodiments of this invention,

Fig. 1 is a view showing a head-dress embodying the invention applied in position upon the head of a person;

Fig. 2 is a perspective view of the improved head-dress;

Fig. 3 is a plan view of the improved head-dress with parts broken away to show the construction; and

Fig. 4 is a fragmentary perspective view 50 of a modified form of the adjustment means.

Referring in detail to the drawing, 10 denotes the body portion of a head-dress embodying the invention, the opposite ends of 55 which may support suitable attaching means 11.

The entire body portion 10 may be made of suitable elastic material such as elastic woven fabric, or the like material of any well known construction, the mid-section 10^a 60 of said portion being relatively narrow while the outer ends 10^b are enlarged or widened to receive the attaching means, 11. By making the mid-section 10^a which has no hair attached thereto narrower than the 65 outer ends, practical means are provided to eliminate the possibility of the uncovered body portion from being exposed to view after the said portion 10 is incorporated in the coiffure.

As seen from Fig. 2, the body portion 10 is formed of a coarse mesh or net like structure to render the device light in weight and to provide supplementary anchoring means for pinning the hair thereto when forming 75 the coiffure. On each side of the mid-section, there is secured a tuft of hair or switch 12 which may be of a color to match the hair of the wearer.

The attaching means 11 may be of any 80 suitable construction such as one or more hair pins and preferably includes a pair of combs 13, one of which is secured to each outer end 10^b of the body portion 10. The combs 13 are preferably fastened on edge 85 14 on the said end 10^b by stitches 15 so that the teeth of the combs 14 have a tendency to extend inwardly along the said portion 10 as shown in Figs. 2 and 3, for assuring a better engagement of the combs 90 within the hair when applied to the head. An ordinary type of comb may be used to bring about the result desired.

In use, the head dress is adapted to be applied to the head of a woman having 95 bobbed hair at a point where the hair is shortest, which is at the back of the head adjacent the nape of the neck. When applying the device, one of the combs is first inserted upwardly in the wearer's hair and 100 then turned or reversed, that is given a rotary motion, and moved downwardly until the comb is firmly anchored. The other comb is similarly inserted while substantially stretching the body portion about the 105 back of the head. After the device has been securely anchored, the tufts of hair 12 are draped about the head in any desired artistic manner to merge into the real hair thereby covering up the short hair of the 110 bobbed head and giving the head of hair the appearance of long hair.

In Fig. 4 is shown a fragmentary part of a mid-section 20 of a modified form of construction of body portion which includes means for permitting a wider range of head sizes than is possible with the embodiment shown in Figs. 2 and 3. Said means may preferably comprise a small buckle 21 and a loop member 22 which are inserted in the mid-section of the two-part body structure 20^a, 20^b in the usual manner with the loop member 22 secured on the part 20^b and the other part 20^a being provided with an extension strap 20^c which is threaded through said loop member and buckle as will be well understood from the drawing.

Another advantage flowing from the provision of a buckle adjusting means lies in the convenience with which the head-dress may be applied. Thus, the buckle may be manipulated to extend the body portion to its maximum limit, as for example by moving the buckle to the right relatively to the strap as shown in Fig. 4. Each comb 13 is then inserted in position in the manner explained above. The buckle is now moved to the left to take in the slack and to provide tension in the body portion which co-operates with the combs 13 or other fastening means to hold the head dress snugly to the head of the wearer.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. A head-dress comprising a two part elastic body portion adapted to pass partially about the head of the wearer, means interposed between the said body parts for adjusting the normal length of the body portion, tufts of hair secured to each elastic

part and attaching means carried by the free end of each part for insertion on the head of a wearer.

2. A head-dress of the character described for use by persons having short hair comprising an elastic body portion of woven fabric, false hair carried thereby, and a comb secured to each end of said elastic portion, the combs being adapted to be successively inserted in a rotary upward and reversed direction in the hair of the wearer, to hold said body portion to the wearer's head, said body portion having a contracted mid-section to permit draping said false hair about the head in a manner to conceal said body portion and to contact with the short hair to give the wearer the appearance of a full head of hair.

3. A head-dress of the character described adapted to convert the bobbed hair coiffure to simulate one of long hair comprising an elastic body portion of woven fabric adapted to fit partially about the head of the wearer, said portion having a mid-section substantially narrower than the end sections, hair carried on the end sections and means for engaging the hair of the wearer secured to said end sections for holding the head-dress in position on the wearer's head.

4. A head-dress of the character described adapted to convert the bobbed hair coiffure to simulate one of long hair comprising a body portion adapted to fit partially about the head of the wearer, said portion comprising two elastic mesh woven fabric parts interconnected by an adjustable buckle, tufts of hair secured to said elastic parts and a comb attached to the outer ends of said parts for holding the head dress in position on the wearer's head.

5. In a head dress device of the character described a body portion adapted to carry hair pieces comprising a two part woven fabric member having an elastic structure formed through each part, an adjustable means connecting said parts for varying the size of said portion and spaced attachment means for said portion to secure the latter in position on the wearer's head.

In testimony whereof I affix my signature.

LOUIS RUFFIO.
